CIGARETTE

Helen Marie Reseska, Brooklyn, N. Y.

Application May 19, 1953, Serial No. 25,109

Term of patent 14 years

(Cl. D85—6)

To all whom it may concern:

Be it known that that I, Helen Marie Reseska, have invented a new, original, and ornamental Design for a Cigarette, of which the following is a specification, reference being had to the accompanying drawing, forming a part hereof.

The drawing figures are stippled to indicate color contrast.

I claim:

The ornamental design for a cigarette, as shown and described.

HELEN MARIE RESESKA.
